CANDLE HOLDER

Lewis W. Zeyher, 101 Kenwood Drive, Cherry Hill, N.J.

Filed July 8, 1963, Ser. No. 75,704

Term of patent 3½ years

(Cl. D48—2)

FIG. 1.

FIG. 2.

The appearance of the undisclosed side is substantially the same as the side shown.

The dominant features of my design for a candle holder reside in the portions shown in full lines with the candles illustrated in broken lines for illustrative purposes only.

I claim:

The ornamental design for a candle holder, as shown and described.
